UNITED STATES PATENT OFFICE.

FRANCIS X. MALOCAY, OF NEW YORK, N. Y., ASSIGNOR TO INTERNATIONAL BANDING MACHINE COMPANY, OF NEW YORK, N. Y., A CORPORATION OF NEW YORK.

CIGAR-BANDING MACHINE.

1,261,832.

Specification of Letters Patent. Patented Apr. 9, 1918.

Application filed June 2, 1917. Serial No. 372,403.

To all whom it may concern:

Be it known that I, FRANCIS X. MALOCAY, a citizen of the United States, and a resident of the city of New York, county of Bronx, and State of New York, have invented, 5 a certain new and useful Improvement in Cigar-Banding Machines, of which the following is a specification.

The object of my invention is to provide 10 a machine which will securely, accurately, rapidly and automatically apply cigar bands to cigars or other articles of this general character.

This invention relates particularly to band 15 applying mechanism adapted to a machine of the general type disclosed in my co-pending application for patent, Serial No. 96,760, although it may be used in conjunction with other machines of its general 20 type.

The particular portion of a cigar banding machine to which this application has reference is the mechanism known as the band folding or wrapping mechanism and an object 25 of this invention is to provide mechanism of this character which will apply bands of various sizes accurately to variously shaped articles without any modification of the machine.

With these objects in view and other objects which may be disclosed herein, I have devised the particular arrangement of parts to be herein disclosed and more particularly pointed out in the appended claims.

Reference is to be had to the accompanying drawing forming a part hereof in which:

Figure 1 is a rear elevation of my improved device,

Fig. 2 is a front elevation of the same, parts being broken away and in section, to reveal the structure,

Fig. 3 is a sectional view on the line 3—3 of Fig. 1, looking in the direction of the 45 arrows,

Fig. 4 is a vertical sectional view of the platen,

Fig. 5 is a bottom view of the same,

Figs. 6, 7 and 8 are diagrammatic detail 50 views illustrating the operation of the machine.

Throughout the various views of the drawings similar reference characters designate similar parts.

As stated above, my improved cigar band-

ing mechanism herein disclosed is particularly adapted to the type of machine shown in my above referred to application for patent, but is, of course, adaptable for use with any type of cigar band applying machine. 60 In the machine disclosed in my application above mentioned, I provide a band holding magazine for retaining a stack of superposed cigar bands. A conveyer receives a band from the stack and as said conveyer 65 proceeds to the band applying mechanism with the band, the gummed end of the cigar band is moistened by suitable moistening means. Thence it proceeds to the band applying mechanism where the moistened band 70 is received and held by suction means, ready for application to the cigar.

In Figs. 1 and 2 of the drawings I have shown the band 3 with its gummed end 4 and ungummed end 5 held by the band applying mechanism ready for application to the cigar 2 which is shown supported on the table 1, of the machine.

Mounted on the table 1 is a boss 6 through which passes a vertically reciprocating rod 30 7 on the upper end of which is secured a boss 8 on the arm 9 of the casing of the device. The casing comprises a front plate 10 and rear plate 11, and these plates 10 and 11 are connected by crossings 12, these 85 crossings being, if desired, formed integral with the rear plate 11, the front plate 10 being secured to them by the screws 13 or other securing means.

The crossings 12 are apertured as at 14 90 to provide for the reciprocation of a vertical rod or tube 15, which has secured to its lower end, the platen 16. The rod 15 is hollow, or is provided with a longitudinally extending duct or port 17 through which suction, to 95 retain the band on the lower surface of the platen, may be exerted. At its upper end the hollow rod 15 is connected to a flexible tube 18 or the like which extends to a plump or any other well known suction supplying 100 device.

A spring 19 surrounds the rod 15 and extends between the upper crossing 12 and a stop 20 secured on the rod, to allow the platen 17 to adjust itself to the varying 105 sizes of cigars, resiliently bear against the cigar 2 and hold the band against the same with resilient pressure.

The front plate 10 and rear plate 11 of the casing are each provided with a pair of 110

parallel ears 21 and pivotally mounted between these pairs of ears 21 is a pair of tape actuating fingers 22 and 23. These fingers are secured to the pivot pins 24, 25, which extend between the ears and are pivotally mounted therein and secured on said pins at one of their ends, on the outer side of the ears, are pinions 26 which mesh with segmental gears 27 and 28, pivoted at 29 and 30 to the rear plate 11 of the casing. The segmental gears 27 and 28 are each provided with lateral arms 31 which are each connected with mechanism to oscillate or rock the segmental gears 27 and 28. The arm 31 on the segmental gear 27 is connected to a lever 32 which extends to suitable cam mechanism or other mechanism to actuate the rod 32 whereby the segmental gear 27 will be rotated about its axis to swing the finger 22 20 to and away from the platen 16 when required. The movement of the segmental gear 27 is restricted by means of a projection 33 formed on it which abuts against a stop 34 on the inner casing plate 11 when 25 the gear reaches the limit of its rotation in one direction and this stop 34 abuts against one of the sides of the segmental gear 27 when the gear reaches its limit of rotation in the other direction. A stop 34^a is also 30 provided for the segmental gear 28 and the movement of this gear in one direction is limited by the shoulder 35^a and in the other direction by its edge in the same manner as with the gear 27.

35 The arm 31 on the segmental gear 28 is connected to a link 35 which extends to one arm of a bell crank lever 36, this lever 36 being pivoted at its angle at 37 between an ear 38, extending from the plate 11, and 40 said plate 11. The other arm on the bell crank lever 36 is connected to a rod or lever 39 which extends to suitable cam mechanism or the like. It will, therefore, be noted that an upward movement of the rod or lever 39, will, through the medium of the mechanism just described, cause the finger 23 to swing toward the platen 16 and a reverse or downward movement of the rod 39 will cause the finger to pivot away from the 45 platen.

50 The platen 16 is provided with a pair of vertically extending side plates 40 which are slotted to provide the members 41. The platen is vertically slotted at 42 and horizontally slotted at 43 to form the prongs or members 44. Detachably secured to the platen is a pair of tapes 45 and 46. These tapes are secured thereto by looping the same over the members 41 and these tapes 55 pass inward through the slots 43 and downward through the slots 42. This structure is clearly revealed in Figs. 4 and 5. It will be noted from the foregoing that the tapes are so positioned that they extend from the 60 platen in opposite directions and in no way

interfere with or obstruct the suction through the tube to cause the band to adhere to the platen.

The tapes 45 and 46 extend over rollers 47 and 48 on the fingers 22 and 23 and the 70 tape 46 has its end secured to a coil spring 49 which extends upwardly and has its end secured to a projecting ear 50 formed on a plate 51 on the inner side of the front casing plate 10. The front casing plate 10 is 75 provided with a longitudinally extending slot 51^a through which a screw 52 on the plate 51 extends. A nut 53 is adjustable on this screw so it will be noted that by loosening this nut the plate 51 may be moved up 80 and down to stretch or relax the spring 49 and a spring attached to the other tape 23, to be described, until the tension desired on the tapes 45 and 46 is obtained.

The end of the tape 45 is secured to a block 85 54 which is movable between a pair of guide plates 55 secured to the casing, and extending upwardly from this block is a coil spring 56 which is substantially like the spring 49 secured to the other tape 46. This spring 9 56 has its upper end secured to an ear 57 formed on the plate 51 and this ear 57 is slotted at 58 to form a guide for a rod 59 secured to and extending upwardly from the block 54.

95 Formed on the rear plate 11 of the casing and extending upwardly therefrom is a lug or ear 60 and pivoted on this ear 60, at 61, is a finger 62 which has one of its ends resting on the rod 59 and its other end resting on the 100 lever or rod 39. A spring 63 extends from the finger 62 to the casing and tends to hold the end of said finger on the end of the rod or lever 39 so that a movement of said rod or lever 39 will actuate the finger 62.

105 It will be noted that an upward movement of the lever 39 will cause the finger 62 to press downwardly on the rod 59 so that tension on the tape 45 is relieved in a manner to be described.

Pivoted to the rear plate 11 of the casing at 64 is a lever 65 having a bent upper end 66, a spring 67 surrounding its pivot and engaging the edge of the lever to draw the lever against a stop 68 on the plate 11.

110 From the foregoing the operation of my improved machine will be readily understood.

115 Referring to Figs. 6, 7 and 8 its operation will be clearly shown. In Fig. 6 I have 120 shown the platen 16, holding a band 3 and resting upon a cigar 2. The finger 22 has pivoted against the cigar and wrapped the tape about the same over the band to cause the ungummed end 5 to be wrapped about the cigar. The finger 23 has pivoted to a position slightly away from the cigar and tension on the tape 45 is relieved by the pressure of the finger 62 on the rod 59 so that the tape 45 is flexed or caused to bulge away 125 130

from the cigar at 69, so that the ungummed end 5 of the band can be tucked in between the gummed end 4 and the side of the cigar. The bulging or flexing of the tape 45 is caused to occur at the point 69 by reason of the stiffness of the paper from which the band is made and the tendency of the band to straighten out. It will, therefore, be noted that bands of varying lengths are readily applicable to cigars of varying diameters as by reason of the means above described the ends of the bands can overlap for a substantially great distance for by reason of the flexing or bulging operation of the tape, above described, the ungummed end of the band can lap clear around to one side of the cigar without contacting with the gummed end during the process of wrapping the ungummed end in position.

20 In Fig. 7 the tape 45 is again placed under tension and I have shown in that view both the gummed end 4 and the ungummed end 5 of the band wrapped about the cigar with the gummed end slightly projecting from 25 between the fingers and awaiting its final sealing pressure. In causing the finger 23 to assume the position shown in Fig. 7 against the cigar, the arm 51 has swung to contact with the lower end of the lever 65 so to cause the same to pivot about its axis 64 so that its bent upper end 66 strikes against the rod 69 and forces the same out from under the finger 62 as disclosed in Fig. 7. As downward pressure on the rod 59 is thus relieved the spring 56 immediately places the tape 45 under tension and draws the same tightly about the cigar to lap the gummed end of the band snugly over the ungummed end.

40 In Fig. 8 I have shown the arm 22 swung away to allow the pressure applying pad 70 to press against the band over the gummed end 4 to seal the ends 4 and 5 together. This pad 70 is mounted on a suitable bracket secured on an arm 71 having a roller 72 which rides on the surface of a table 73. After this pressure has been applied, the platen suction is released and both fingers 22 and 23 are swung away to allow 50 the removal of the banded cigar by mechanism which forms no part of this invention and which therefore need not be described. After the cycle of the operations above referred to is completed it is repeated in like 55 manner for each cigar to be banded.

From the foregoing it is obvious that my invention is not to be restricted to the exact embodiment herein shown, but is broad enough to cover all structures coming within the scope of the annexed claims.

What I claim is:—

1. In a machine of the class described, means for wrapping a cigar band about a cigar comprising a pair of tapes under tension, means for causing one of said tapes

to fold one end of the band about the cigar, means for relieving the tension of the other tape while said end is being folded and means for placing said tape under tension after the end of the band has been folded, 70 to fold the other end of the band over the first-mentioned end.

2. In a machine of the class described, a pair of tapes for wrapping a band about a cigar, a finger for actuating each of said 75 tapes, means for tensioning said tapes and mechanism for automatically releasing the tension on one of said tapes while one end of the band is being wrapped about the cigar.

3. In a machine of the class described, a pair of tapes for wrapping a band about a cigar, said tapes being under tension, a finger for each of said tapes to actuate the same, mechanism for actuating one of said 85 fingers to first cause the tape actuated by it to wrap the ungummed end of the cigar band about the cigar, mechanism for causing the tension on the other tape to be relieved while said ungummed end of the band 90 is being wrapped and mechanism for causing said tape to be again placed under tension after the folding of the ungummed end of the band has been effected.

4. In a machine of the class described, 95 means for holding a cigar band, a pair of tapes for wrapping said band about a cigar, a pivoted finger for each of said tapes to actuate the same, means for tensioning said tapes and means for relieving the tension of 100 one of said tapes during a period in the application of the band to the cigar.

5. In a machine of the class described, succession means for holding a cigar band, a pair of tapes extending longitudinally of the 105 band to wrap the same about the cigar, a pivoted finger for each of said tapes to actuate the same, means for oscillating said fingers about their axes, tension means for the tapes for normally holding the same under tension and means for relieving the tension of one of said tapes during a period in 110 the application of the band to the cigar.

6. In a machine of the class described, a platen, suction means on said platen to hold a cigar band thereon, a pair of tapes secured to said platen and extending therefrom over pivoted fingers for actuating said tapes, mechanism for moving said fingers to cause the same to wrap the tapes about a cigar 120 over the cigar band, tension means for said tapes and means for relieving the tension of one of said tapes during a period in the application of the cigar band to the cigar.

7. In a machine of the class described, a 125 pair of tapes for wrapping a band about a cigar, springs on the ends of said tapes to hold the same under tension, a finger for each of said tapes to actuate the same and means for relieving the tension of one of 130

24. the tapes exerted by the spring secured to it during a period in the application of the band to the cigar.
8. In a machine of the class described, a platen, means for holding a band to the platen, a pair of tapes secured thereto, a pivoted finger for each of said tapes to actuate the same, a spring secured to each of said tapes to hold the same under tension, a mechanism for pivoting one of the fingers to cause it to actuate its tape to apply the ungummed end of the band about the cigar, means for relieving the tension of the other tape while said ungummed end is being applied, means for pivoting the other finger against the cigar and means for placing the said tape under tension after the gummed end of the band has been applied. 70
9. In a machine of the class described, a platen, a pair of tapes secured thereto for wrapping a band about a cigar, tension means on the tapes to hold the same under tension, a finger for each of said tapes to actuate the same, means for relieving the tension of one of said tapes during the application of the band to the cigar and means for exerting pressure on the ends of the cigar band after the same has been applied. 75
10. In a machine of the class described, a pair of tapes for wrapping a band about a cigar, a finger for each of said tapes to actuate the same, means for tensioning said tapes, a block secured to one of said tapes, a rod extending from said block, and a finger for engaging said rod and moving the same to relieve the tension on said tape during a period in the application of the band to the cigar. 80
11. In a machine of the class described, a pair of tapes for wrapping a band about a cigar, a finger for each of said tapes to actuate the same, means for tensioning said tapes, a block secured to one of said tapes, a rod extending from said block, a pivoted finger for engaging said rod and moving the same to relieve the tension on said tape, and means for moving the rod out of engagement with the finger. 85
12. In a machine of the class described, a pair of tapes for wrapping a band about a cigar, a finger for each of said tapes to actuate the same, means for tensioning said tapes, a block secured to one of said tapes, a rod extending from said block, a pivoted finger engaging the rod and means for moving the same to cause said finger to move the rod to relieve the tension on the tape and a lever for engaging the rod to move the same out of engagement with the finger. 90
13. In a machine of the class described, a platen comprising a plate with vertical sides, members on said sides to engage tapes, said tapes being adapted to wrap a band about a cigar, a pivoted finger for each of said tapes to actuate the same, springs on the ends of said tapes to place the same under tension, mechanism for relieving the tension of one of said tapes at a period in the application of the band and mechanism for placing said tape again under tension. 95
14. In a machine of the class described, a band applying mechanism comprising a frame, a platen vertically movable in said frame, means for allowing suction to pass through said platen whereby a band is held on the lower end of said platen, tapes and mechanism for actuating the same to cause said tapes to wrap the band held by the platen about a cigar, springs on the ends of said tapes extending to the frame, a block secured to one of said tapes, a rod projecting from said block, a pivoted finger on the frame for pressing on said rod to stretch the spring to which said block is secured and thereby release the tension on the tape to 100 which said spring is secured. 100
15. In a machine of the class described, a frame, a suction tube mounted to move therein, a platen secured to the lower end of said tube, vertical sides on said platen, tapes secured to said sides, oppositely disposed slots in said platen, and band wrapping tapes secured to the vertical sides of the platen and extending through said slots. 105
16. In a machine of the class described, a frame, a suction tube mounted to move therein, a platen secured on the end of said tube, inwardly extending slots in the sides of said platen extending toward the center of the same, slots extending downwardly from the inner ends of said inwardly extending slots and band wrapping tapes secured to the sides of the platen and extending through the inwardly extending slots toward one another and then downwardly 110 through the downwardly extending slots. 110
17. In a machine of the class described, a frame, a suction tube mounted therein, a platen secured on the end of said tube, a central duct extending through the tube and 115 through the platen, inwardly extending slots in the sides of said platen extending toward the duct in the same, slots extending downwardly from the inner ends of said inwardly extending slots, and band wrapping tapes secured to the platen and extending through the inwardly extending slots toward one another and downwardly on each side of the duct through the downwardly extending slots. 120

Signed at the city, county and State of New York, this 31st day of May, 1917.

FRANCIS X. MALOCSAY.
